UNITED STATES PATENT OFFICE.

JAMES F. VERNER, OF NEW YORK, N. Y.

CAR-FENDER.

SPECIFICATION forming part of Letters Patent No. 718,292, dated January 13, 1903.

Application filed October 18, 1902. Serial No. 127,771. (No model.)

To all whom it may concern:

Be it known that I, JAMES F. VERNER, a citizen of the United States, residing at New York, in the county of New York and State of New York, have invented certain new and useful Improvements in Car-Fenders, of which the following is a full and complete specification, such as will enable those skilled in the art to which it appertains to make and use the same.

The object of this invention is to provide an improved fender or guard for tramway-cars which is simple in construction and operation and by means of which the serious and sometimes fatal accidents which result from a person being struck by a tramway-car when in motion may be avoided.

The invention is fully disclosed in the following specification, of which the accompanying drawings form a part, in which the separate parts of my improvement are designated by suitable reference characters in each of the views, and in which—

Figure 1 is a plan view of one end of a tramway-car provided with my improved fender or guard; Fig. 2, a side view thereof; and Fig. 3, a partial section on the line 3-3 of Fig. 1, only the platform of the car being shown in connection with the fender or guard.

In the drawings forming part of this specification I have shown at *a* a tramway-car provided with the usual platform *a*, and in practice I connect with the bottom of the platform at the opposite sides thereof hangers *b*, through which is passed a rod *c*, from which is suspended supplemental hangers or side bars *d*, which are connected by transverse rods *e* and *f*, the rod *f* being at the bottom thereof and the rod *e* near the top, and the supplemental hangers or side bars *d* are provided at their upper ends with backwardly-directed shoulders or projections *d*², which bear on the bottom of the platform. The supplemental hangers or side bars *d*, together with the rods *e* and *f*, constitute a swinging frame, which is supported by the rods *c*; but the said frame cannot swing backwardly farther than the vertical position, or that shown in Figs. 2 and 3.

Pivotedly connected with the rod *f* is a supplemental forwardly-directed frame *g*, comprising side bars connected at their forward

ends by a transverse cross head or member *g*², rearwardly of which are rollers *g*³, mounted in the sides of the supplemental frame *g*, and the rear ends of the side bars of the supplemental frame *g* are bent upwardly at right angles to the bottom portions thereof, as shown at *g*⁵, and connected, by means of links *g*⁶, with an auxiliary frame *h*, which is pivoted to the rod *e* and which extends forwardly beyond the supplemental frame *g* and which comprises side members *h*², connected by a front cross head or bar *h*³ and a transverse bar *h*⁴, which in the normal position of the parts is over the front end of the supplemental frame *g*, and between the front end of the auxiliary frame *h* and the bar *h*⁴ thereof is placed a wire work or netting *h*⁵, and a similar wire work or netting *g*⁷ is connected with the front portion of the supplemental frame *g* and with the rod *e*. As thus constructed the auxiliary frame *h* normally rests on the front end of the frame *g*, and if a person be struck by the front end of the frame *h* when the car is in motion such person will either be thrown onto the network *h*⁵ and onto the network *g*⁷, or if the front end of the frame *h* be raised, so as to pass over said person, the front end of the frame *g* will be depressed and the person will be thrown onto the frame *g* and onto the network *g*⁷.

It is apparent that if any object or animal be struck by the fender or guard when the car is in motion the result would be the same as above specified.

The connection of the frame *h* with the frame *g* by means of the links *g*⁶ is such, as will be apparent, to produce the result above set out, both of said frames being pivoted at *e* and *f*, respectively, and the raising of the front end of the frame *h* will depress the front end of the frame *g*, as will be readily understood, and when the front end of the frame *g* is depressed the rollers *g*³ will move on the rails of the track, which are shown at *i*.

The entire fender or guard may also be swung forwardly and upwardly and may be held in an upright position in any desired manner, this operation resulting from the method of connecting the hangers *d* or the frame of which said hangers form a part with the bottom of the platform *a*.

Having fully described my invention, what

I claim as new, and desire to secure by Letters Patent, is—

1. A fender or guard for tramway-cars comprising a main frame hinged to the bottom of the platform and adapted to be folded forwardly and upwardly, a supplemental frame pivoted to the bottom of the main frame and projecting forwardly and provided with upwardly-directed rear end extensions, an auxiliary frame pivoted in the top of the main frame and projecting forwardly beyond the forward end of the supplemental frame, said auxiliary frame being also loosely connected with the upwardly-directed rear end members of the supplemental frame, substantially as shown and described.
2. A fender or guard for tramway-cars comprising a main frame hinged to the bottom of the platform and adapted to be folded forwardly and upwardly, a supplemental frame pivoted to the bottom of the main frame and

projecting forwardly and provided with upwardly-directed rear end extensions an auxiliary frame pivoted in the top of the main frame and projecting forwardly beyond the forward end of the supplemental frame, said auxiliary frame being also loosely connected with the upwardly-directed rear end members of the supplemental frame, said supplemental frame and the forward end of the auxiliary frame being each provided with wire mesh or network, substantially as shown and described.

In testimony that I claim the foregoing as my invention I have signed my name, in presence of the subscribing witnesses, this 16th day of October, 1902.

JAMES F. VERNER.
